UNITED STATES PATENT OFFICE

WILLIAM P. CROCKETT AND WILLIAM P. CROCKETT, JR., OF CHICAGO, ILLINOIS,
ASSIGNORS TO HOSPO, INC., OF CHICAGO, ILLINOIS, A CORPORATION OF ILLINOIS

ELECTRIC LIGHT FIXTURE

Application filed December 5, 1930. Serial No. 590,163.

The invention relates to electric light fixtures, and particularly to that type of fixture which may be removably attached to furniture, wall brackets or other supports.

5 The primary object of the invention is to provide an electric light fixture which may be readily attached to or detached from a support so as to furnish illumination to the user at the particular place or spot desired, and 10 the invention is therefore particularly applicable for use in hospitals, physicians', surgeons' and dentists' offices where close examinations and explorations are frequently made and where portability of the lamp is de- 15 sirable. The invention is also of particular utility in laboratories, studios, garages, and in fact in any place where light must be brought close to the person or object to be examined. It will be obvious that the electric 20 light fixture is also particularly adaptable for use as a reading lamp.

Another object of the invention is to provide the fixture with means whereby one portion of the fixture may be firmly attached to 25 another portion of the fixture and locked into place so that it cannot be casually separated or removed, and yet by properly manipulating the locking mechanism, the light fixture portion may be very readily detached from 30 the clamping or supporting portion of the fixture.

A further object of the invention is to provide a structure which will maintain the clamping portion of the fixture and the handle and reflector portion thereof in locked 35 relationship except on operation of the locking mechanism involving coacting locking features in both portions of the fixture.

In connection with the detachable feature 40 of the fixture to enable the lamp to be used as a hand lamp or portable lamp in connection with examinations or explorations, it is an important object of the invention to be able to quickly and readily lift the lamp from 45 its support, and as quickly and readily replace it and lock it in position, and therefore the support and the lamp fixture are provided with spaced coacting locking means so that the lamp fixture may be placed at any one 50 of a plurality of positions in the holder and

locked into place, and the reflector can thereupon be rotated to its desired position.

It is a further object of the invention to encase the electric light socket and the light cord in a cylinder adapted to serve the double 55 purpose of providing a portion of the detachable locking means and providing a handle for the fixture so that the fixture may be readily grasped, removed from its holding and clamping portion and brought to the 60 place or location for the examination and exploration by the physician, surgeon, dentist, nurse, or other person.

A further object of the invention is to combine a rotating reflector with the handle 65 so that the direction of the light rays may be controlled.

It is a further object of the invention to construct the handle in such a manner that a socket having pull chains or cords for varying 70 the volume of light from the lamp may be used.

An additional object of the invention is to provide adjustable clamping means for the 75 supporting portion of the fixture so that the fixture may be secured to any size or form of bed or other support.

A modified structure is shown and described, wherein the supporting portion of the electric light fixture is permanently associated with and secured to a wall box, or fastened to the wall, or other place, as desired, but allowing the ready adjustment of the lamp with its reflector and handle. 80

The invention will best be understood by reference to the accompanying drawings wherein the principle structure and the modification are shown, it being understood that we do not limit ourselves to the exact constructions shown and illustrated but in the 85 claims hereinafter set forth intend to cover all variations and modifications thereof.

In the drawings:

Figure 1 shows an assembly and side view 90 of the electric light fixture with its clamp attached to the top rail of a bed,

Figure 2 is a disassembled view of the structure of Figure 1 and shows the manner 95 of handling the portable portion of the fix-

ture as well as the clamping and supporting portion of the fixture,

5 Figure 3 is a horizontal sectional view of the clamping screws of the fixture on the line 3—3 of the right hand portion of Figure 2,

10 Figure 4 is a longitudinal sectional view of the electric light fixture illustrated in Figure 1,

15 Figure 5 is a front view of the face of the supporting portion of the fixture shown clamped to the top rail of a bed,

20 Figure 6 is a front or face view of the end of the handle showing the studs which fit and lock in the clamping and holding portion of the fixture and showing the rear view of the reflector,

25 Figure 7 is an end view of a portion of the supporting part of the fixture and showing the lamp and handle in locked position,

30 Figure 8 is an enlarged sectional view of locking elements shown in Figure 4,

35 Figure 9 is a view showing the under side of the reflector and the handle and illustrates the pull chains in the handle,

40 Figure 10 is an oblique sectional view showing the locking connection between the handle and supporting portions of the fixture on the line 10—10 in Figures 5 and 6,

45 Figure 11 is a side elevation of the assembly of a modified form of electric light fixture with clamp attached to be permanently secured in a wall fixture.

50 Figure 12 is a disassembled side view of the electric light fixture and support shown in Figure 11, and illustrates the electric light fixture being held separately from the support,

55 Figure 13 is a longitudinal cross sectional view of a supporting portion of the modified form of fixture and support and

60 Figure 14 is a top view of the electric light fixture in place in the modified form of wall support.

65 Like parts throughout the various views are given the same reference characters.

As illustrated in Figures 1 to 10 inclusive, of the drawings, the electric light fixture comprises the clamping mechanism generally designated 20, the support 21, the handle generally designated 22, the latter carrying the reflector 23. The lamp socket 24 is shown in position in the handle and the lamp bulb 25 is in position within the reflector.

70 As shown the electric light fixture is clamped to the top square tube or rail 26 of the bed 27. It will be obvious that the fixture may be clamped to a round tube or rail of a bed or in fact any portion of a bed to which the jaws of the clamp may be fitted. It will also be understood that the electric light fixture may be clamped to any kind of furniture, apparatus or support to which the jaws of the clamp may be fixed.

75 The clamp of the fixture is provided with

a pair of jaws 28 and 29 which preferably have the angularly disposed depending portions as shown. These depending portions or arms when brought toward each other by the means about to be described, securely clamp and hold the fixture to the bed or other support.

80 In order to assist the clamp in maintaining a secure grip or hold on the bed or support, protectors 30 and 31 of suitable form and material, such as sheet rubber, are used. By the employment of the rubber protectors, which preferably cover the entire inner faces of the clamp-arms, the electric light fixture is prevented from rotating or from any movement on the rail of the bed, however smooth it may be.

85 Each of the depending arms of the clamp are provided with hollow tubes which extend into each other and telescope so as to permit any desired adjustment of the two clamping arms. The outer clamping arm 29 is provided with two telescoping tubes 32 and 33. The tubes 32 and 33 are driven and permanently fitted into apertures in the clamp arm 29, and extend entirely through the clamp arm 29 as particularly shown in Figure 3. It will be understood that the tubes 32 and 33 are immovable with respect to the clamp arm 29.

90 The bore of the tubes 32 and 33 is smooth to receive the closely fitting tubes 34 and 35 which are permanently fitted in the clamp arm 28 and extend entirely through the apertures in the clamp arm 28, and through the 100 U shaped member 36 on the inner side of which the tubes are turned and held.

95 The interior faces of the tubes 34 and 35 are screw threaded to receive the long screws 37 and 38. These screws are passed through the tubes 32 and 33 into the tubes 34 and 35 to the desired position. The clamp arms 28 and 29 are then brought to their desired position on the bed, table or other support. The screws 37 and 38 are provided with the 110 permanently attached hexagonal heads 39 and 40, and also the cup shaped washers 41 and 42 to cover the apertures in the clamp arm 29 and the exposed ends of the tubes 32 and 33.

115 It will be understood that the cup shaped washers may be screw threaded on the screws 37 and 38, or they may be permanently secured to the screws against the heads 39 and 40.

120 The rubber protector 30 is provided with apertures to enable the tubes 34 and 35 to pass therethrough to enable the protectors to be placed against the inner face of the clamp arm 28. The rubber protector 31 is 125 also provided with apertures to enable the tubes 32 and 33 to pass therethrough so that the rubber protector may be fitted against the inner face of the clamp arm 29.

130 After sliding the arm 29 and the tubular

extensions 32 and 33 on the extensions 34 and 35, the screws in the tubular extensions 34 and 35 meanwhile remaining in the position to which they have been brought, the 5 clamp is set in position on the rail 26, or other support, and the clamp arm 29 and extensions 32 and 33 slide on the extensions 34 and 35 until the arms 28 and 29 clamp the rail 26.

The screws 37 and 38 are thereupon screwed 10 into the tubular extensions 34 and 35 to securely balance and clamp the arms 28 and 29 against the rail 26, or other support.

As a general proposition in connection 15 with hospital beds the clamp and holder will usually remain on the bed in the same position in which it was originally placed but it will be understood that the clamp and holder may readily be moved to any part of the bed, and the clamp being adjustable may 20 readily be fitted and secured in position.

The support 21 is pivotally connected to the clamp generally designated 20 by means of the U shaped member 36 and the pivot pin 43, and screw head 44. The pivot pin 43 is 25 provided with the head 45 and the reduced stem 46. The reduced stem 46 is screw threaded to pass into the screw threads in the interior of the screw head 44. The screw head 44 is provided with a head 47. The pivot pin 43 and the screw head 44 are each closed by the sleeve 48.

The support 21 is provided with the extended portions or flanges 49 which are apertured and through which apertures the pivot 35 pin 43 and the screw head 44 extend. The extended portions or flanges 49 are between the U shaped member 36 and the heads 45 and 47 of the pin 43 and the screw head 44, respectively. The screw head 47 when turned 40 will draw the pin 43 so that a tight and snug fit of the various parts will be made.

The support 21 is also provided with a plurality of keyhole slots 50, 51, 52 and 53 for the reception of the studs 54, 55, 56 and 57 45 which are on the lamp handle generally designated 22. The support 21 is also provided with two apertures 58 and 59. These apertures 58 and 59 are for the passage and reception of the locking pin or stud 60 and the 50 push button stem 61. These studs or stems are permanently affixed, as by solder, to a flat locking spring 62, riveted at 63 to the main wall of the support 21.

Push button stem 61 is provided with the 55 head 64 which extends outwardly of the support 21 and is positioned below the handle 22 when it is in normal position in the support 21. The support 21 is also provided in its upper portion with the large slot 65 having the enlarged opening 66. The slot 65 is to enable the cord 67 to be passed through it and into the enlarged opening 66 and thereupon permits the sleeve or thimble 68 to pass into and become seated in the enlarged opening 66 of the support.

The handle 22 is composed of the cylindrical container 69 which is formed with the annular reduced portion 70 at the lamp end. A ring 71 having an angular flange, is seated on the shoulder formed by the reduced portion 70. A washer 72 is then placed on the ring 71 and the apertured reflector 23 is then placed in position against the washer. 70

Locking rings 73 are then placed in position against the reflector to hold the reflector 23 in place. The ring 71 is provided with an outward screw thread and the rings 73 are provided with corresponding interior screw threads. The reflector 23, the ring 71 with its ring washer 72, and the locking rings 73 80 are so arranged and held in such a position that the reflector is frictionally held in place, but is permitted to rotate 360 degrees by the application of a suitable degree of force. 75

The lamp socket 24 is provided with the 85 thimble end 74 which is screw threaded on its interior to receive one end of the tubular cord extension pipe 75. The outer end portion of the tubular cord extension pipe has exterior screw threads for connection with the 90 end thimble 68. The end portion of the conductor 67 is passed through the thimble 68, the tubular cord extension pipe 75, and to the lamp socket 24, where its end is properly connected to the lamp socket to supply current. 95

The cylindrical holder 69 is provided with the longitudinal slot 76, the inner end of which slot is enlarged to receive the pull chain thimble 77 secured in the lamp socket 100 24. The lamp pull chains 78 and 79 extend through the thimble 77 into the socket 24 and operate the lamp 25.

The cylindrical holder 69 is covered with several sections of insulated fiber tubing 80 and 81. The section of fiber tubing 80 is placed on the outside of the handle 69 before the socket 24 is inserted into the handle. After the socket 24, the tubular extension 75 and the cord 67 have been inserted in the handle they are placed at the end thereof, the pull chain thimble passing along the slot 76. The other section of fiber tubing is passed along the cord 67 and placed in position abutting the fiber tubing section 80. The fiber tubes are cut out to fit around the pull chain thimble. 110 115

A metallic cap 82 is fitted on the end of the handle and is secured to the fiber tube 81 and the metallic cylindrical holder 69, by a plurality of screws 83 which pass through screw-threaded apertures in the flange of the metallic cap 82, the fiber tube section 81 and the metallic holder 69. 120

The metallic cap 82 which has the plurality of studs 54, 55, 56 and 57, is also provided with a plurality of apertures 84, 85, 86 and 87, which are for the reception of the locking pin 60 on the flat spring 62. The apertures 84, 85, 86 and 87 are preferably spaced 125 130

around the face of the metallic cap between the studs 54, 55, 56 and 57. As shown more particularly in Figure 10, the studs 54, 55, 56 and 57 have enlarged heads and reduced necks and are inserted and riveted into the metallic cap with portions of the necks with the heads thereon extending beyond the face of the metallic cap.

It will thus be seen that after the lamp 10 socket extension tube and cord have been inserted in the handle and the fiber tubes, and the metallic cap, with the light cord extending through it, has been secured in position by the said screws, first having the end of 15 the cord extension tube screw threaded into the thimble in the metallic cap, the electric light fixture is complete as a portable lamp structure and may thus be used when the conductor is properly connected in the lighting 20 circuit.

When it is desired to place the electric light fixture, which has been used as a portable lamp, in place in the support 21, the conductor 67 is passed into the slot 65, to the enlarged opening 66 and the portable fixture is then pushed into place against the support 21. At this time the thimble 68 should be in alignment with the aperture 66, the heads of the studs 54, 55, 56 and 57, should be in 25 alignment with the enlarged portions of the keyhole slots 50, 51, 52 and 53, respectively, and one of the apertures 84, 85, 86 or 87 should be near the locking pin or stud 60.

The face of the support 21 is thereupon 30 brought directly against the face of the metallic cap 82. In this position the thimble 68 and the heads of the studs 54, 55, 56 and 57 extend through the aperture 66 and the slots 50, 51, 52 and 53, respectively, beyond the 35 inner face of the support 21. The lamp fixture is then slightly rotated in the keyhole slots and in the opening 66 until the studs pass to the end of the restricted or narrow portions of the slots 50, 51, 52 and 53, whereupon the locking pin 60 attached to the flat spring 62 snaps into one of the apertures 84, 40 85, 86 or 87.

In order to release the lamp structure from the support 21, pressure is applied on the button 64, and the stem 61 secured to the flat spring 62 to withdraw the locking stud or stem 60 from the particular aperture 84, 55 85, 86 or 87. When this release has been effected the lamp structure is rotated slightly in the opposite direction around the thimble 68 so that the studs 54, 55, 56 and 57 pass from the restricted or narrow portions of the keyhole slots 50, 51, 52 and 53 to the enlarged portions of the slots whereupon the fixture may be withdrawn from the support, the thimble 68 passing through the opening 66 and the conductor 67 passing upwardly through the slot 65. The lamp structure thereupon again becomes a portable one and may be used for 60 exploration and examination as desired.

In the modified structure illustrated in Figures 11 to 14, inclusive, the same electric lamp structure and support as is shown in Figures 1 to 10, inclusive, is employed. The difference in the two structures is that instead of having the fixture provided with a clamping portion such as the clamping portion 20, the fixture and support are attached to a U shaped member 88 which in turn is riveted to a wall plate 89 by means of the 70 rivets 90 and 91.

The wall plate 89 bearing the U shaped member which carries the support 21 and the electric light fixture is preferably inserted back of the ordinary wall plate 92 which covers the wall outlet box 93, with which the plug 94 is associated.

It will therefore be understood that in this last described structure the electric light fixture is portable but the fixture support and the connection with the wall plate is not portable but is permanently fixed in position.

The latter type of structure is especially adapted for physicians', surgeons' and dentists' offices, laboratories, garages and other 90 places where only the portable light fixture itself needs to be moved about.

It will also be understood that in addition to the portability of the holder portion of both forms of electric light fixtures, in each case the holder portion may be swung downwardly or upwardly on the pivot connections 43 and 44, if it is desired not to have the holder portion extending horizontally from the clamp and support.

Having thus described the invention what we claim and desire to secure by Letters Patent is:

1. In an electric light fixture the combination of a cylindrical holder, said holder being adapted to receive an electric light socket, said holder being adapted to receive a reflector and at the other end a cap, a support for said holder attached to a clamping mechanism, said support and the face of said cap being provided with coacting adjustable and detachable means whereby said holder and reflector may be held in various positions or may be entirely separated from said support and clamp.

2. In an electric light fixture the combination of a cylindrical holder, said holder being adapted to receive an electric light socket, said holder being adapted to receive a reflector at one end, and a cap at the other end, clamping mechanism, a support for said holder attached to said clamping mechanism, said support and the face of said cap being provided with coacting adjustable and detachable means whereby said holder and reflector may be held in various positions or may be entirely separated from said support and clamp, said adjusting and detaching means consisting of a plurality of studs and slots spaced in said cap and support.

3. In an electric light fixture the combination of a cylindrical holder, said holder being adapted to receive an electric light socket, said holder being also adapted to receive a reflector at one end and a cap at the other end, clamping mechanism, a support for said holder attached to said clamping mechanism, said support and the face of said cap being provided with coacting adjustable and detachable means whereby said holder and reflector may be held in various positions or may be entirely separated from said support and clamp, said adjusting and detaching means consisting of a plurality of 10 studs and slots spaced in said cap and support, said clamping mechanism consisting of two clamping jaws operatively connected at both sides thereof near the upper corners thereof by a pair of telescoping and reciprocating members.

4. In an electric light fixture the combination of a holder adapted to contain an electric light socket, a support, clamping mechanism, said support and clamping mechanism being pivotally connected, said support and holder being adjustably and detachably connected by means of a plurality of key-hole slots and studs adapted to fit therein, said clamping mechanism consisting of two 25 clamping arms operatively connected at both sides thereof by a pair of telescoping and reciprocating tubes, one of said telescoping tubes having screw threads on its interior and said telescoping and reciprocating tubes 30 being held with said clamping arms in closed relationship by a screw within said screw threaded member.

5. In an electric light fixture the combination of a holder adapted to contain an 40 electric light socket, said holder being connected with a support and a clamp at one end and at the other end having a reduced annular portion with a shoulder on said holder, a ring with a flange adapted to seat on 45 said shoulder surrounding said reduced portion, a reflector, said reflector being adapted to rotate 360 degrees at all times and said reflector being held against said flanged ring by a pair of locking rings.

6. In an electric light fixture the combination of a holder adapted to contain an electric light socket, said holder being adapted to receive a rotating reflector at one end and a cap at the other end, a support, clamping mechanism, said support and clamping mechanism being pivotally connected, said support and holder being adjustably and detachably connected, said support having a plurality of keyhole slots therein, said cap being provided with a plurality of studs adapted to fit in said keyhole slots, said support being provided further with a spring locking mechanism, said cap being provided with a plurality of apertures and said spring lock mechanism being adapted to coact with

either of said apertures to lock and unlock said holder and support.

7. In an electric light fixture the combination of a holder adapted to contain an electric light socket, a support, clamping mechanism, said support and clamping mechanism being pivotally connected, said support and holder being adjustably and detachably connected by means of a plurality of key-hole slots and studs adapted to fit 70 therein, said clamping mechanism consisting of two clamping arms, pairs of telescoping and reciprocating tubes connected to each of said clamping arms one on each side of said clamping mechanism and near the upper corners thereof, the inner of said tubes having interior threads and a pair of screws adapted to screw into said interior tubes to hold said clamping arms against an object to which said light fixture is to be 75 clamped.

8. In an electric light fixture the combination of a holder adapted to contain an electric light socket, said holder being adapted to receive a rotating reflector at one end and a cap at the other end, a support, clamping mechanism, said support and clamping mechanism being pivotally connected and said support and holder being adjustably and detachably connected, said support having a plurality of keyhole slots therein, said cap being provided with a plurality of studs adapted to fit in said keyhole slots, said support being provided further with a spring lock mechanism, said locking mechanism having a button for unlocking said support and holder, the head of said button being beneath said cap, said cap being provided with a plurality of apertures and said spring lock mechanism being adapted to coact with either of said apertures to lock and unlock said holder and support.

9. In combination a clamp, an adjustable flat face carrier plate carried thereon, a portable lamp, a stud and slot for disconnectably associating said carrier plate and portable lamp, and a spring latch for maintaining them in associated relation.

10. In an electric light fixture, the combination of a holder, said holder being adapted to receive an electric light socket, said holder having a cap at one of its ends, a support for said holder, said cap being provided in its face with a plurality of studs, said support being provided with a plurality of slots, said studs on said cap being adapted to fit in said slots in said support whereby said holder may be held in said support in various positions.

11. In an electric light fixture the combination of a holder, said holder being adapted to receive an electric light socket, said holder having a cap at one of its ends, a support for said holder, said cap being provided in its face with a plurality of studs, said studs having necks and enlarged heads, said

support being provided with a plurality of keyhole slots, the enlarged heads of said studs on said cap being adapted to enter said keyhole slots in said support and on turning in said keyhole slots said studs being adapted to engage and to be held by said support in various positions.

12. In an electric light fixture, the combination of a holder, said holder being adapted to receive an electric light socket, said holder having a cap at one of its ends, a support for said holder, said cap being provided in its face with a plurality of studs, said support being provided with a plurality of slots, said studs on said cap being adapted to fit in said slots in said support whereby said holder may be held in said support in various positions, said support being provided with a lock comprising a spring pressed button, said cap being provided with apertures, said spring pressed button being adapted to lock and unlock said holder and support.

13. In an electric light fixture the combination of a holder, said holder being adapted to receive an electric light socket, said holder having a cap at one of its ends, a support for said holder, said cap being provided in its face with a plurality of studs, said studs having necks and enlarged heads, said support being provided with a plurality of keyhole slots, the enlarged heads of said studs on said cap being adapted to enter said keyhole slots in said support and on turning in said keyhole slots said studs being adapted to engage and to be held by said support in various positions, said support being provided with a lock comprising a spring pressed button, said cap being provided with apertures, said spring pressed button being adapted to lock and unlock said holder and support.

14. In an electric light fixture the combination of a holder, said holder being adapted to receive an electric light socket, said holder having a cap at one of its ends, a support for said holder, said cap being provided in its face with a plurality of studs, said studs having necks and enlarged heads, said support being provided with a plurality of keyhole slots, the enlarged heads of said studs on said cap being adapted to enter said keyhole slots in said support and on turning in said keyhole slots, said studs being adapted to engage and to be held by said support in various positions, said support being provided further with a spring locking mechanism, said locking mechanism having a button for locking and unlocking said support and holder, the head of said button being beneath said cap when the holder and the support are in locked position, said cap being provided with a plurality of apertures and said spring lock mechanism being adapted to coact with either of said apertures to lock and unlock said holder and support in various positions.

15. In an electric light fixture the combi-

nation of a holder, said holder being adapted to receive an electric light socket, said holder having a cap at one of its ends, a support for said holder, said cap being provided in its face with a plurality of studs, said studs having necks and enlarged heads, said support being provided with a plurality of keyhole slots, the enlarged heads of said studs on said cap being adapted to enter said keyhole slots in said support and on turning in said keyhole slots, said studs being adapted to engage and to be held by said support in various positions, said support being provided further with a spring locking mechanism, said locking mechanism having a button for locking and unlocking said support and holder, the head of said button being beneath said cap when the holder and the support are in locked position, said cap being provided with a plurality of apertures and said spring lock mechanism being adapted to coact with either of said apertures to lock and unlock said holder and support in various positions, the apertures in the face of said cap being spaced between the studs extending from said cap.

In witness whereof, we hereunto subscribe our names this 3rd day of December A. D., 1930.

WILLIAM P. CROCKETT.
